(57) **CLAIM**

The ornamental design for a wallet, as shown and described.

DESCRIPTION

FIG. 1 is a front and bottom perspective view showing of a wallet showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wallet in folded state; and, FIG. 10 is another perspective view of the wallet in folded state.

The broken lines in the figures illustrate portions of the wallet that form no part of the claimed design.

1 Claim, 10 Drawing Sheets
